United States Patent Office

Des. 191,018
Patented Aug. 1, 1961

191,018

VENTILATOR

Ralph E. Kearney and Elmer H. Haman, both of
2323 25 N. 11th St., Philadelphia, Pa.

Filed Sept. 29, 1960, Ser. No. 62,301

Term of patent 14 years

(Cl. D62—3)

Fig. 1.

Fig. 2.

Fig. 3.

Fig. 4.

FIGURE 1 is a side elevation of a ventilator showing our new design;

FIGURE 2 is a top plan view thereof;

FIGURE 3 is a vertical section taken on the line 3—3 of FIGURE 2; and

FIGURE 4 is a bottom plan view of the ventilator.

The undisclosed sides of the ventilator are the same as the side shown.

We claim:

The ornamental design for a ventilator, as shown and described.
